UNITED STATES PATENT OFFICE.

HENRY W. PLEISTER, OF WESTFIELD, AND JOHN KARITZKY, OF GARWOOD, NEW JERSEY, ASSIGNORS, BY MESNE ASSIGNMENTS, TO HENRY B. NEWHALL, OF PLAINFIELD, NEW JERSEY.

EXPANSION BOLT.

1,417,198.

Specification of Letters Patent. Patented May 23, 1922.

Application filed April 2, 1921. Serial No. 458,081.

To all whom it may concern:

Be it known that we, HENRY W. PLEISTER, a citizen of the United States, residing at Westfield, in the county of Union and State of New Jersey, and JOHN KARITZKY, a citizen of the United States, residing at Garwood, in the county of Union and State of New Jersey, have made certain new and useful Improvements in Expansion Bolts, 10 of which the following is a specification, taken in connection with the accompanying drawings.

Our invention relates to expansion bolts and more particularly to the combination of 15 an expansion bolt and an escutcheon plate; and also to the expansion bolt as a separate article of manufacture.

Our invention further relates to such a 20 combined expansion bolt including an escutcheon plate that has a maximum grip or hold in the ceiling or wall for a given size of expansion. Our invention further relates to an expansion, the outer end of 25 which in use is adapted to lie substantially flush with the surface of the ceiling or wall, or may be moved slightly back in the hole, and a removable escutcheon plate attached to it.

Our invention further relates to an expansion having a neck provided with an interior groove and a plurality of cutaway 30 portions or notches, and an escutcheon plate having fingers or engaging surfaces to pass through said notches into the groove and 35 then be rotated slightly, either by hand or by the bolt used with the expansion.

Our invention further relates to certain 40 combinations, details of construction, and articles of manufacture, which will be more fully hereinafter described and pointed out in the claims.

In the accompanying drawings the same reference numerals refer to similar parts in the several figures.

Fig. 1 is a vertical section through a ceiling or other suitable support, showing our expansion bolt partly broken away for purposes of clearer illustration;

Fig. 2 is a plan view of the interior surface of the escutcheon plate; 50

Fig. 3 is a side elevation of the escutcheon plate;

Fig. 4 is an end elevation of this expansion;

Fig. 5 is an end elevation of the combined 55 expansion and escutcheon plate, showing the first attaching position, wherein the escutcheon plate is eccentric with relation to the longitudinal axis of the expansion;

Fig. 6 is an end elevation, similar to Fig. 60 5, showing the escutcheon plate partially rotated from the position shown in Fig. 5, so as to make it concentric with the longitudinal axis of the expansion.

It has been proposed to secure a removable cap or plate to an expansion bolt, the head of which is permitted to extend out of the opening in the wall or ceiling a sufficient distance to become imbedded or seated in, and enclosed by, a hollow removable 70 plate. Among other disadvantages this is objectionable in that the expansion is not inserted its full length in the hole and therefore its effective expansion surface is materially lessened. To carry a given load a 75 larger expansion is required than one in which the expansion bolt proper is inserted for its whole length within the hole. It is further objectionable in that it brings a powerful expansion force near the outer surface of the wall or ceiling which is apt to cause the surface or wall to crack around the hole, requiring a larger plate than if the expansion force was thrown well back into the hole and removed from the surface of 85 the wall or ceiling.

By our invention we permit the full length of the expansion to be inserted in the wall, ceiling or other suitable support, and therefore insure that the powerful expansion is exerted well back from the surface of the wall or ceiling, thereby insuring both a stronger expansion for a given size of expansion bolt, and also protecting the surface of the wall or ceiling from cracking 90 or crumbling as the expansion force is ap-

plied to the expansion bolt. This permits us to use an escutcheon plate of the minimum size and therefore one requiring less metal and cheaper to manufacture. Being 5 relatively small it is less obtrusive and enhances the appearance of the job.

In the drawings we have shown one embodiment of our invention in which 1 is any suitable expansion, having interior locking 10 surfaces 2, preferably formed as a groove in the neck 3. We have shown for purposes of illustration the expansion 1 as a machine expansion formed of the two parts 4 and 5 which are forced apart by the wedge 6 carried by the nut 7; the nut being provided 15 with interior screw threads to cooperate with the male threads upon the bolt 8. The members 4 and 5 are also preferably, though not necessarily, provided with parallel ribs 9, 9 to engage with the walls of the hole 10 in 20 the ceiling or other support 12. The form of the expansion is immaterial for it may be operated by a machine bolt, a lag screw or any other suitable means. It must, however, be provided with a neck such for 25 example as 3, in which engaging locking surfaces are formed.

The escutcheon plate 13 is provided with locking means to cooperate with the expansion 30 1 so that in the first attaching position the parts will not be concentric; that is, the center of the escutcheon plate 13 will not at first be concentric with the longitudinal axis of the expansion 1. By rotating the escutcheon plate, with relation to the expansion, the parts will be brought into concentric relation with each other. They are held 35 in concentric relation by means of the bolt so that they cannot be removed, one from the other, as long as the bolt is connected with the expansion. The escutcheon plate may be partially rotated by hand or by the mere 40 insertion of the bolt 8.

Various means may be employed to 45 accomplish this, all of which come within the terms of our invention. We have shown by way of example one such arrangement, but of course it is to be understood that our invention is not to be limited to the particular construction shown. We provide the escutcheon plate 13 with the fingers 14 and 15 which are shown in Fig. 2 as being 180 degrees apart. The neck 3 of the expansion is provided with the cutaway portions or 50 notches 16 and 17, Fig. 4, so arranged that when the fingers 14 and 15 are brought opposite to their respective notches 16 and 17 the center of the escutcheon plate will be out of line, or eccentric with the longitudinal 55 axis of the bolt anchor 1. We have shown such an arrangement in Fig. 4. In first positioning the escutcheon plate 13 the finger 15 is brought in line with the notch 16 and the finger 14 in line with the notch 17, and then

pressed in slightly until the ends of the 65 fingers reach the groove 2 in the neck 3. The parts are then eccentric, as shown in Fig. 5. The escutcheon plate is then rotated slightly so as to cause the end of the finger 14 to engage behind the shoulder 18, 70 as shown in Figs 1 and 6. This rotation may be by hand or by merely inserting the bolt 8. In this position the parts are concentric and are held concentric by the bolt 8. They cannot be brought back into the eccentric 75 position shown in Fig. 5, preparatory to disconnecting the escutcheon plate from the expansion, as long as the bolt 8 is in the expansion. When, however, the bolt 8 has been withdrawn it is a comparatively simple 80 matter to bring the parts into the eccentric position shown in Fig. 5, and disconnect the escutcheon plate from the expansion, should this be desirable at any time.

Our invention is adapted for universal 85 use and is particularly useful in hanging pipes to ceilings and walls, as for example, in automatic fire sprinkling installations. The pipes are supported by the bolt 8. By the use of our invention we not only reduce 90 the cost of installation, but insure a stronger grip for an expansion bolt of a given size and also insure a more finished and better artistic effect for the entire installation.

Having thus described this invention in 95 connection with an illustrative embodiment thereof, to the details of which we do not desire to be limited, what is claimed as new and what is desired to secure by Letters Patent is set forth in the appended claims. 100

What we claim is:—

1. The combination of an expansion bolt having a neck provided with an interior groove, said groove having notches arranged at less than 180° apart adapted to receive 105 the concentric lugs of an escutcheon plate.

2. An expansion bolt comprising a shield having internal locking surfaces to cooperate with an escutcheon plate, an escutcheon plate having concentric locking surfaces to enter the locking surfaces of the shield eccentrically, a bolt to locate the escutcheon plate and its concentric bearing surfaces concentrically with the longitudinal axis of the shield thereby preventing detachment of 110 the escutcheon plate from the shield. 115

3. The combination of an expansion shield having a neck provided with an interior groove with slots extending from the extremity of the shield into the groove, said 120 slots arranged at less than 180° apart, an escutcheon plate provided with concentric lugs to engage said groove and means to hold the concentric lugs on the escutcheon plate concentric with the axis of the shield 125 to prevent its extraction in an eccentric position through the slots.

4. The combination of an expansion bolt

and an escutcheon plate both having cooperating locking means whereby they may be made to engage in eccentric position and then be locked by rotating to concentric position.

5. The combination of an expansion bolt and an escutcheon plate both having cooperating locking means whereby they may be made to engage in eccentric position and 10 then be locked by rotating to concentric position, a bolt, said bolt adapted to bring

the locking means from the eccentric locking position to the concentric locking position.
